UNITED STATES PATENT OFFICE.

THOMAS H. TOWELL, OF CLEVELAND, OHIO, ASSIGNOR TO THE UNITED STATES PHONOGRAPH COMPANY, OF CLEVELAND, OHIO, A CORPORATION OF OHIO.

HORN FOR TALKING-MACHINES.

1,033,215.

Specification of Letters Patent. Patented July 23, 1912.

Original application filed July 29, 1910, Serial No. 574,467. Divided and this application filed March 18, 1912. Serial No. 684,443.

To all whom it may concern:

Be it known that I, THOMAS H. TOWELL, a citizen of the United States, and a resident of Cleveland, county of Cuyahoga, 5 and State of Ohio, have invented a new and useful Improvement in Horns for Talking-Machines, of which the following is a specification, the principle of the invention being herein explained and the best mode in which 10 I have contemplated applying that principle, so as to distinguish it from other inventions.

The present invention, relating as indicated to horns for talking machines, has as 15 its object the provision of a horn suitable for use on such machines, whether of the disk or cylinder type, and one that will be readily adjustable to the various requirements encountered in operating either such 20 type of machine.

The subject matter of the present case has been divided out of applicant's co-pending application Serial No. 574,467, filed July 29, 1910, and relates more especially to the 25 amplifier as distinguished from such amplifier in combination with the talking machine mechanism.

To the accomplishment of the end just recited said invention, then, consists of the 30 means hereinafter fully described and particularly pointed out in the claims.

The annexed drawing and the following description set forth in detail certain mechanism embodying the invention, such dis- 35 closed means constituting, however, but one of various mechanical forms in which the principle of the invention may be used.

In said annexed drawing:—Figure 1 is 40 a side elevation of one typical form of cylinder talking machine, with a horn shown in connection therewith embodying the present improvement; Fig. 2 is a horizontal sectional detail of such horn, taken on the plane 2—2, Fig. 1; Fig. 3 is a vertical section of 45 a detail of the jointed elbow connecting the tone arm with the amplifier proper; and Fig. 4 is similarly a vertical section of the forward end of said tone arm, the pitch of the coiled interlocking strip composing such 50 tone arm being exaggerated in order to render the construction of the latter clear.

Only the outline of the talking machine proper, together with the case or cabinet upon which it is mounted, is shown in Fig.

1, and it will be understood that the type 55 of the machine is entirely immaterial so far as the improvements herein claimed are concerned. In other words, for example, said machine may be of the disk record type instead of the cylinder type illustrated. 60

The horn is designed to be supported upon a bracket 1 extending rearwardly and upwardly from such cabinet, and comprises in effect three portions, a tubular elbow 2 pivotally mounted upon the bracket in question about a vertical axis, an amplifying horn 3, and an extension 4 that forms the sound-conveying connection between the small end of said amplifier and the sound-box 5 of the talking machine. The 70 openings of such tubular elbow are substantially right-angularly related, and it is with the upwardly directed one that the amplifying horn is connected, being pivotally secured to the elbow by a sectional flange 6, 75 as clearly shown in Fig. 3. One section of such flange is detachably secured in place by a set-screw 18, whereby the horn may be entirely removed from the elbow. Said horn is furthermore constructed in one or 80 more sections which may be separated, as at the joint 7, if desired, to facilitate packing in case of shipment or storage, the horn being more or less in the way when not in use. Pivotal movement of horn 3 upon the 85 bracket is limited in either direction by a stop 16 carried by the other section of such flange and co-operating with a segmental notch or recess 17 in the edge of the horn, as will be readily understood. The elbow 80 2 is thus pivotally mounted about an upwardly directed pin or stud 8 on the bracket 1, and is designed to be normally fixedly secured, or in other words, held against rotation, by means of a set screw 9, that co- 95 operates with such pin. It is not designed that such elbow shall have any movement about this pin in the normal use of the horn, such pivoting being merely provided in order to enable the horn to be swung to 100 one side, in case it becomes desirable to entirely disconnect the same from the sound-box.

The sound conveyer 4 extending from the small end of the horn 3, or rather from the 105 horizontally directed opening of the elbow 2, to the sound-box comprises a section of flexible metallic tubing, a preferred con-

structural form of such tubing being that shown in the sectional view of Fig. 4, from which it will be seen to consist of coiled interlocking strips 10 of metal, with an interposed packing strip 11. Such sound-conveyer is furthermore made tapering to conform with the taper of the amplifying horn and elbow so that, in other words, there is a continuous and general increase in the 10 diameter of the bore of the passage formed by such extension, elbow and the amplifier proper.

The larger end of the conveyer is received in an annular socket or recess 12 formed in 15 the casting constituting the elbow, while a ferrule or sleeve 13 is similarly fitted over the smaller end of such conveyer, one end of the short recurved tube, or elbow 14, that connects the sound conveyer with the sound-box 20 being designed to slidably fit within such sleeve, just as the other end of such tube 14, fits slidably over the upwardly extending tubular portion of the sound-box 5.

The flexible character of the sound-conveyer permits the sound-box to travel across the record upon the record support 15 with perfect freedom, while still preserving a direct connection with the amplifier. The bore, moreover, of such conveyer, increases 30 gradually in diameter in accordance with the well known principle of acoustics, so that the sounds emanating from the sound-box are reproduced in perfect tone and undiminished volume. The horn proper may 35 obviously be swung so as to extend in any desired direction without interfering in the slightest with the flexing of the sound conveyer although the stop 16 prevents any turning of the horn to an extent that might 40 overbalance the machine. When it is desired to remove the horn this is readily accomplished by releasing the set-screw 18 that holds the detachable section of the retaining flange in place. Should it, furthermore,

become necessary or desirable to entirely 45 disconnect the sound conveyer from the sound-box in order to get at the machine, this may be accomplished by simply loosening set-screw 9, when the elbow, together with the sound conveyer and amplifier attached thereto, may be swung to one side. 50

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A horn for talking machines, comprising a generally tapering amplifying horn proper, and a flexible tubular extension to the smaller end of said horn consisting of coiled interlocking strips, such extension being tapered to conform with the taper of said amplifying horn. 60

2. A horn for talking machines, comprising a generally tapering amplifying horn proper, and a flexible tubular extension to 70 the smaller end of said horn consisting of coiled interlocking strips of metal, such extension being tapered to conform with the taper of said amplifying horn.

3. A horn for talking machines, comprising a curved amplifying horn proper of generally tapering form pivotally supported at its smaller end, and a flexible tubular extension to such smaller end consisting of coiled interlocking strips of metal, 80 such extension being tapered to conform with the taper of said amplifying horn.

Signed by me this 14th day of March, 1912.

THOMAS H. TOWELL.
